UNITED STATES PATENT OFFICE.

KRISTIAN HOLTER AND OLAF QVILLER, OF OLSO, NORWAY.

SIEVE PLATE FOR SCREW PRESSES.

Application filed April 15, 1926, Serial No. 102,286, and in Norway February 2, 1926.

Screw presses for removing water from cellulose and other aqueous substances in a pasty or pulp-like form are afflicted with the drawback that the pulp layer located 5 next to the sieve plate is compressed to such a degree as to prevent any further removal of water from the parts of the pulp locating nearer the axis. This results in no advantages being obtained by extending the sieve 10 plate beyond the end of the screw.

The present invention has for its object to provide an arrangement, whereby it will be possible to break up the tight and dry layer or covering located next to the sieve plate 15 resulting in turn in the possibility of pressing out water from the inner part of the pulp layer.

According to the invention the last portion of the sieve plate, either in the proximity of or beyond the point, where the screw 20 terminates, is constructed with an increased circumference, whereby the tight pulp layer adhering to the sieve plate is divided or broken up and channels are formed through 25 which water from the inner portions of the pulp can be pressed out and be conducted through the sieve perforations.

In the drawing some constructional forms 30 of the invention are illustrated. Figures 1, 2, 3, 5 and 6 show the last portion of the screw press in longitudinal section in five different forms. Figure 4 is a cross section 35 on the line IV-IV of Figure 3. Similar reference numbers have the same meaning in all figures.

Referring to Figure 1, the press screw 1 is surrounded by the cylindrical sieve plate 2, which is in turn spacedly surrounded by the outer casing 3. 5 is the outlet compartment. Between the outlet 5 and the point, where the screw 1 terminates, the sieve plate

is continued in the form of annular portions the diameter of which increases in steps as shown at 4.

According to Figure 2 the widened extension 45 of the sieve plate is made by means of an outwardly tapering section 4 with perforations.

Figures 3 and 4 illustrate a third constructional form. As will be seen, the portion 4 50 of the sieve plate located between the screw end and the outlet is made with a square cross section instead of a circular-cylindrical section, whereby the same result is obtained.

Figure 5 shows a construction representing 55 a border case of the construction indicated in Figure 2. The tapered portion 4 of the sieve plate is made with an apex angle equal to 180°, consequently in the form of a plane disc.

According to Figure 6 the screw is not terminated at the point where the widening 60 of the cross section commences but it continues through the extended portion 4 with 65 decreasing diameter, thus in effect still further enhancing the cross sectional area of the outlet.

Claim:

In a screw press for removing water from 70 aqueous substances, pulps etc., the combination of a screw, a sieve plate surrounding the screw having an outlet end, said sieve plate in a zone adjacent to the outlet being made with a polygonal cross section, where- 75 as the other part of the sieve plate is made circular in cross section.

In testimony whereof we have signed our names to this specification.

KRISTIAN HOLTER.
OLAF QVILLER.
